UNITED STATES PATENT OFFICE

VERNON E. CORNELL, OF CLEVELAND, OHIO, ASSIGNOR TO CORNELL SECURITIES CORPORATION, OF CLEVELAND, OHIO, A CORPORATION OF DELAWARE

METALLIC RECEPTACLE AND CLOSURE THEREFOR

Application filed August 26, 1930. Serial No. 477,820.

My invention is an improvement in metallic receptacles and closures therefor and relates more particularly to means for removably clamping covers on containers such as 5 metallic barrels.

One of the objects of my invention is to provide a simple means for clamping the heads on metallic barrels and other receptacles for storing and shipping liquids such 10 as oil, in the form of a split, channelled, contractible clamping ring for drawing the flange of the cover tightly down against the bead of the barrel to form a liquid-tight seal between the cover and receptacle.

Another object of my invention is to provide a removable clamping device for clamping the heads on metallic receptacles such as 15 barrels, which is self-locking when contracted and which may be easily removed from the receptacle to permit access into the interior thereof.

Other objects and advantages of my invention will be more readily understood from the following description of an embodiment 20 thereof, reference being made to the accompanying drawing in which like reference characters are employed to designate like parts throughout the same.

Fig. 1 is a side elevation of a metallic receptacle showing my invention applied in use.

Fig. 2 is a plan view of the same.

Fig. 3 is a fragmentary section of the receptacle showing the clamping ring in place 35 and tightly clamping the cover on the receptacle.

Fig. 4 is a fragmentary view of adjacent ends of the split clamping ring showing the same separated when the ring is expanded.

Fig. 5 is a section through an end of the ring taken on line 5—5 of Fig. 4.

Fig. 6 is a sectional view taken on line 6—6 of Fig. 4.

In the drawing I have illustrated an embodiment of my invention applied to a metallic receptacle 1 such as a barrel. The receptacle is usually provided at its open end with a bead rolled outwardly as at 2. A cover 3, having an outwardly extending, annular, 50 concavo-convex flange 4 fits into the open end

of the receptacle as shown, the flange 4 being supported by the bead 2 of the receptacle. An annular packing 5 may be interposed between the flange 4 and the bead 2 to provide a cushion seat for the flange and to further insure a liquid seal when the cover is tightly clamped down on the bead. 55

In carrying out my invention as illustrated in the drawing I provide a channelled, split clamping ring 6, which, in cross section is substantially C shaped. One end of the ring is slightly enlarged for a portion of its length as indicated at 7 for receiving the other end of the ring 8, in telescopic relation when the ring is contracted about the end of the receptacle for clamping the cover thereon. 65

I have provided means for securing the ends of the split ring together in interlocked relation when the ring is contracted. This means includes one or more projections or 70 fingers 9 which are preferably formed integrally with the ring material and extend outwardly of the ring end 8 into the path of similar projections or fingers 10 formed on the ring end 11. 75

The respective fingers are preferably formed by stamping the same in the ring material and deflecting them outwardly and inwardly respectively in substantially parallel planes to each other. The formation of these 80 fingers may be better understood by referring more particularly to Figs. 4, 5, and 6 of the drawing, it being noted that where a plurality of such fingers is employed as shown, an opening is provided in the ring material 85 between each adjacent finger for receiving the respective fingers of the other end of the ring when the two ends are telescoped one within the other in ring contracted position. The fingers formed in each end of the ring extend 90 preferably at an acute angle away from the end walls of the respective ends of the ring.

I have also provided means whereby the ring may be engaged by a suitable tool for contracting the ring in assembling and disassembling it from the receptacle. This means consists in up-setting a portion of the ring material as at 12 and forming an opening through the ring material for receiving a suitable tool for drawing the ring ends together. 100

By my invention I have provided a very simple and inexpensive clamping device for clamping the heads or covers on metallic receptacles which when contracted about the 5 cover and the bead of the receptacle tightly draws the cover and bead together to form a liquid-tight seal therebetween. I have also provided means whereby the clamping ring may be easily removed if desired to permit 10 access to the interior of the receptacle. A clamping ring constructed in accordance with my invention will not become loosened accidentally even though it may be subjected to severe shock as by dropping the barrel or 15 from other causes.

My invention is intended primarily for use with metallic containers of relatively heavy gage material as, for instance, sheet steel from 10 to 18 standard gage. Liquids such as oil 20 are stored or shipped in these containers and a liquid tight seal between the bead and the mouth of the container is very essential in such case. By the use of my invention, such a seal may be maintained while the ring is 25 contracted.

Various changes may be made in the details of construction and arrangement of parts without departing from the spirit of 30 my invention or the scope of appended claims.

30 I claim:

1. The combination with a metallic receptacle having an annular bead rolled about its open end and a cover for the receptacle having a marginal outwardly extending concavo- 25 convex flange for supporting the cover on the bead, of an annular contractible clamping ring engaging the bead and the cover flange and channelled to overlie and underlie the flange and bead to draw the same tightly together when the ring is contracted, and interlocking means formed integrally with the ring and located at points on the ring for clamping the ring tightly about the cover and the bead when the ring is contracted.

45 2. The combination with a metallic receptacle having an annular bead rolled about its open end and a cover for the receptacle having a marginal outwardly extending flange for fitting the cover on the bead, of a split, 50 contractible clamping ring engaging the bead and the cover flange and channelled to overlie and underlie the flange and bead to draw the same tightly together when the ring is contracted, the respective ends of the ring telescoping one within the other when the ring is contracted, and cooperating means formed integrally with the ring ends for securing the ends of the ring together in interlocked telescopic relation when the ring is contracted.

60 3. The combination with a metallic receptacle having an annular bead rolled about its open end and a cover for the receptacle having a marginal outwardly extending flange for fitting the cover on the bead, of 65

a split, channelled, contractible clamping ring engaging the bead and the cover flange to draw the same tightly together when the ring is contracted, the respective ends of the ring telescoping one within the other when the ring is contracted, and cooperating means formed integrally with the ring ends for securing the ends of the ring together in interlocked telescopic relation when the ring is contracted, said means including 70 a plurality of projections pressed from the ring material and extending in substantially parallel planes, each of the projections on one end of the ring intersecting the plane of the wall of the other end of the ring. 75

4. The combination with a metallic receptacle having an annular bead rolled about its open end and a cover for the receptacle having a marginal outwardly extending flange for fitting the cover on the bead, of a split, channelled, contractible clamping ring engaging the bead and the cover flange to draw the same tightly together when the ring is contracted, the respective ends of the ring telescoping one within the other when the ring is contracted, and cooperating means formed integrally with the ring ends for securing the ends of the ring together in interlocked telescopic relation when the ring is contracted, said means including 80

85 a plurality of projections pressed from the ring material near the respective ends of the ring, the projections of each ring section being in substantially parallel planes, and the areas between the projections on each ring section being apertured to receive the projections of the other ring section to secure the ends of the ring together in interlocked relation when the ring is contracted about the bead and the 90 cover. 95

5. In a clamping device for a metallic receptacle having an annular bead rolled about its open end and a cover for the receptacle having a marginal outwardly extending concave-convex flange for supporting the cover on the bead, an annular contractible clamping ring engaging the bead and the cover flange said ring being channelled to overlie and underlie the flange and bead to draw the same tightly together when the ring is contracted, and interlocking means formed integrally with the ring and located 100 at spaced points along the ring ends for clamping the ring tightly about the cover and the bead when the ring is contracted. 105

6. In a clamping device for a metallic receptacle having an annular bead rolled about its open end and a cover for the receptacle having a marginal outwardly extending flange for fitting the cover on the bead, a split, 110 contractible clamping ring engaging the bead and the cover flange and channelled to overlie and underlie the flange and bead to draw the same tightly together when the ring is contracted, and cooperating means formed integrally with the ring ends for securing the ends of the ring together in interlocked telescopic relation when the ring is contracted. 115

120 6. In a clamping device for a metallic receptacle having an annular bead rolled about its open end and a cover for the receptacle having a marginal outwardly extending flange for fitting the cover on the bead, a split, contractible clamping ring engaging the bead and the cover flange and channelled to overlie and underlie the flange and bead to draw the same tightly together when the ring is contracted, the respective ends of the 125 130

ring telescoping one within the other when the ring is contracted, and a series of spaced cooperating means formed integrally with the ring ends for securing the ends of the 5 ring together in interlocked telescopic relation and distributing the closing forces uniformly between the engaged cooperating means when the ring is contracted.

7. In a clamping device for a metallic receptacle having an annular bead rolled about its open end and a cover for the receptacle having a marginal outwardly extending flange for fitting the cover on the bead, a split, contractible clamping ring engaging 15 the bead and the cover flange and channelled to overlie and underlie the flange and bead to draw the same tightly together when the ring is contracted, the respective ends of the ring telescoping one within the other when 20 the ring is contracted and cooperating means formed integrally with the ring ends for securing the ends of the ring together in interlocked telescopic relation when the ring is contracted, said means including a plurality 25 of projections pressed from the ring material and extending in substantially parallel planes, each of the projections on one end of the ring intersecting the plane of the wall of the other end of the ring.

29 8. In a clamping device for a metallic receptacle having an annular bead rolled about its open end and a cover for the receptacle having a marginal outwardly extending flange for fitting the cover on the bead, a split, contractible clamping ring engaging 35 the bead and the cover flange and channelled to overlie and underlie the flange and bead to draw the same tightly together when the ring is contracted, the respective ends of the 40 ring telescoping one within the other when the ring is contracted, and cooperating means formed integrally with the ring ends for securing the ends of the ring together in interlocked telescopic relation when the ring is

45 contracted, said means including a plurality of projections pressed from the ring material near the respective ends of the ring, the projections of each ring section being in substantially parallel planes, and the areas between 50 the projections on each ring section being apertured to receive the projections of the other ring section to secure the ends of the ring in interlocked relation when the ring is contracted about the bead and the cover.

55 9. A clamping device for a receptacle and cover therefor comprising a ring channelled to overlie and underlie adjacent portions of the cover and receptacle and split transversely 60 whereby the ends of the ring are telescoped one within the other when the ring is contracted, and interlocking means formed integrally with the ring adjacent each end thereof, said means including a plurality of 65 projections pressed from the ring material extending in substantially parallel planes,

certain of the projections on one end of the ring intersecting the plane of the wall of the other end of the ring.

10. A device for clamping a cover on a receptacle, comprising a ring channelled to 70 overlie and underlie adjacent portions of the cover and receptacle split transversely whereby the ends of the ring are telescoped one within the other when the ring is contracted, each of said ring ends being formed for telescoping interlocked engagement one with the other by having portions pressed from the ring material at spaced intervals to form a plurality of interlocking teeth separated by 75 openings in the ring material to receive the teeth of the other ring end and thereby uniformly distributing the closing forces between the engaged interlocking teeth.

In testimony whereof, I hereunto affix my signature. 80
